J.L. Burdick.
Printing Press.

No 17,418.

Patented June 2, 1857.

UNITED STATES PATENT OFFICE.

JASON L. BURDICK, OF NEW YORK, N. Y.

PRINTING-PRESS.

Specification of Letters Patent No. 17,418, dated June 2, 1857.

To all whom it may concern:

Be it known that I, JASON L. BURDICK, of New York, in the county and State of New York, have invented a new and Improved 5 Printing-Press; and I do hereby declare that the following is a full and exact description thereof, reference being had to the accompanying drawings and to the letters of reference marked thereon.

10 Figure I represents a longitudinal section of the press showing the type roller drawn quite back. Fig. II is a side elevation and Fig. III is a longitudinal section showing the type cylinder drawn back half way.

15 Similar letters represent similar parts.

A is a roller having a straight surface (*p*) to receive the type. This roller receives a forward and backward motion through the connecting rods C, connected with the crank 20 shaft S, which latter is either moved by hand through the lever L or by any other mechanical power. This roller A is guided in suitable slides Q on the main frame B and is capable of turning with its axle while 25 moving backward and forward.

D, D', are arms attached to the connecting rods C, on each end of the type roller A, and receive only a very slight motion, subject to the vibrating motion of the connecting rods. The lower arms D carry the inking roller, J, which is made to press 30 always against the circumference of the type roller A, and the upper arms D' support and guide the distributing rollers R in 35 such a manner as to allow the same to adjust themselves always by their own weight to the surface of the roller A or to the type attached to the straight surface, *p*.

H is a small rack attached on the outside 40 of the machine to the frame B and into which the pinion P, fast on the end of the axle, O, of the roller A works. G, is a guide piece fastened likewise on the outside of the frame B and so constructed that as 45 soon as the pinion P leaves the stationary rack H, a long projecting tooth (*m*) on said pinion P, enters said guide piece G, and is then thereby moved and guided in any desired direction.

50 During the backward motion of the roller A the teeth of the pinion P come into the stationary rack H, in consequence of which a rotating motion is communicated to the

type roller A at the same time said roller is moved backward, during which time the inking roller J will distribute the ink all over the surface of the roller A. When the type roller A is moved again forward, the same receives through this pinion P, in connection with the stationary rack H a 60 reverse rotating motion, when the distributing rollers R take up the ink from the circumference of the roller A and distribute the same over the types, while the same move under said rollers R. The pinion P through 65 which, as above described, the rotating motion has been communicated to the type roller A, leaves the stationary rack H, as soon as the types, attached to said roller A, have passed from under the distributing 70 rollers R and before the forward motion of the type roller A is completed. The projecting tooth, *m*, comes then into the guide piece, G, by which this pinion and consequently the type roller A is brought into the 75 required position and is thereby guided in that position during the completion of its forward motion, so that the type will come perfectly square against the paper or card on the platen T.

80 The platen T is attached to the frame B by means of a bolt (*n*) and capable of turning around the same. The lower end of said platen T is connected by rods *v* and *w* with the lower arm D in consequence of which a motion is communicated to said platen, during the backward motion of the type roller A, so as to facilitate the taking out 85 of the printed paper or card and to replace a new one, while during the forward motion of said roller A, the platen T is brought back again into its original position, so as to offer a square surface to the type on the roller A. The position of the bolt (*n*) is exactly in a line with the center of the 90 type roller A and the line of motion of said roller, and whereas this type roller A is guided by the guide piece G during the latter part of its forward motion, so as to move in a straight line any slight deviation 95 of the platen T will easily adjust itself.

100 What I claim as my invention and desire to secure by Letters Patent, is—

1. The arrangement of working the roller A, upon which the type is attached, in such 105 a manner as to communicate to the same a

forward and backward motion in connection with a rotating motion substantially as described.

2. I claim the arrangement of a guide piece, for the purpose of guiding the type roller in the latter part of its forward motion, so as to bring the types always square

against the platen T containing the paper or card to be printed.

JASON L. BURDICK.
